DECORATIVE CEILING TILE

George H. Amundson, Minneapolis, Minn., assignor to Minnesota and Ontario Paper Company, Minneapolis,
Minn.

Filed Aug. 19, 1963, Ser. No. 76,284

Term of patent 14 years

(Cl. D18—2)

FIG. 2

The rear of the decorative ceiling tile is substantially plain.

I claim:

The ornamental design for a decorative ceiling tile, substantially as shown and described.
